UNITED STATES PATENT OFFICE.

ARTHUR J. BRIGGS, OF SYRACUSE, NEW YORK, ASSIGNOR TO NATIONAL CARBON COMPANY, INC., A CORPORATION OF NEW YORK.

SPACER FOR DEPOLARIZING BOBBINS.

Application filed April 14, 1924. Serial No. 706,515.

This invention relates primarily to centering and insulating means for dry cell depolarizing bobbins. More particularly, the invention comprises an improved insulating 5 spacer adapted to receive the bottom of the bobbin and to hold it positively in central position in the zinc container electrode.

Bobbins have heretofore been provided with various forms of bottom insulating 10 members, such as paraffined paper cups, flexible sheets having their corners or marginal serrations upturned about the bobbin, and analogous devices. These accomplish more or less satisfactorily the essential result 15 of keeping the bobbin out of actual contact with the zinc.

But the prior bottom caps and the like do not generally insure the accurate centering of the bobbin. The inner diameter of the 20 zinc container ordinarily exceeds that of the bobbin, plus the thickness of its encircling spacing member, by an amount which allows the bobbin considerable freedom of movement. The position of the bobbin is in such 25 case largely determined by the way in which it is inserted. In quantity production it is obviously impractical to use the care necessary to insert the bobbin centrally in every cell. A large part of the output, therefore, 30 will have the bobbin decidedly off center, either initially or by subsequent shifting of the bobbin with respect to the container. Further, prior spacing devices usually 35 obstruct electrolytic action upon a portion of the zinc surface and cause irregular corrosion of other portions.

It is highly desirable that the bobbin be accurately centered, as otherwise serious disadvantages may arise, such as excessive zinc 40 corrosion on restricted areas, and danger of short circuiting. In accordance with the present invention, there is provided an insulating spacer which positively holds and centers the bobbin, without attendant disadvantages.

Reference is to be made to the accompanying drawing, in which:—

Fig. 1 is a perspective view of a dry cell including the improved spacer, the zinc cup 50 being partly broken away;

Fig. 2 is a vertical section through the cell of Fig. 1;

Fig. 3 is a plan view of the spacer as it appears before insertion in a cell; and

Fig. 4 is a view similar to Fig. 3, showing 55 a modified form of spacer.

Referring to Figs. 1 to 3, numeral 1 denotes a mix bobbin inserted in a zinc cup 2 and adapted to be embedded in electrolyte paste, not shown. The spacer 3, in which the present invention resides, comprises in a preferred form a sheet 4 of suitable insulating material having tangs 5. The sheet has approximately the outline and dimensions of a hexagon inscribed in a circle having a diameter approaching the inner diameter of the cup. The rounded corners 6 on the sheet therefore lie closely adjacent to the wall of the cup and lateral movement is prevented. Further, the tangs when upturned 70 define a seat adapted to receive snugly a bobbin of average size. The bobbin is accordingly retained in the desired central position, since its seat is positively centered by engagement of the spacer with the cell 75 wall.

The new spacer, used in cell manufacture on a commercial scale, has very materially reduced the percentage of defectively assembled cells. An important feature of the invention is the attainment of this result without substantially disturbing the electrolytic action. The active zinc surface is engaged by the apex only of each tang 5 and there are no obstructing areas between bobbin and 85 zinc of sufficient extent to cause objectionably localized action.

It will be clear that the spacer will function though the bobbins be somewhat over size or under size. In either case the tangs 90 limit the position of the bobbin to a restricted central area and prevent contact with the zinc.

The principle of the invention may be applied in other forms of spacer. It is essential only that there be two effective marginal portions, one for engaging the cell wall and the other for engaging the bobbin. For example, in Fig. 4, a disk 7 having tangs 8 is illustrated. The diameter of the disk 100 approaches the inner diameter of the cup, and the tangs are struck up on the circumference of a circle which corresponds in area to the base of the bobbin.

The number of bobbin-engaging and cell-engaging portions may of course be varied. It is preferable to score the material lightly at the base of the tangs, to facilitate their

bending. Pulpboard impregnated with paraffin is a suitable material for the spacers, but other insulating materials may be used. Where it is desired to expose the bottom of 5 the zinc cup to electrolytic action, the spacer may be made of permeable material. The bottom of the cup in such circumstances may be thickened or reinforced, as described in an application of H. W. Heise and E. A. 10 Schumacher, Serial No. 680,249, filed December 12, 1923.

15 The spacer may be placed in the bottom of the zinc cup before pouring in the electrolyte and inserting the bobbin, but the preferred method of assembly is as follows: The required amount of paste is poured into the cup, the spacer is pushed into the cup to a point about one-half inch below its brim, and the bobbin is then placed on the spacer 20 and forced to the bottom of the cup. The paste flows upward between the tangs into operative position about the bobbin. Other procedures are also suitable, such as fitting the spacer over the bobbin before inserting it. 25

30 The improved spacer is especially adapted for use with dry cell bobbins provided with no surface protecting means. The spacer tends to prevent the bottom of the bobbin from crumbling, which is frequently encountered when unprotected bobbins are used. The spacer is of course advantageous 35 in other connections, including wrapped bobbin assemblies. While primarily intended as a spacing and centering means for small dry cells of the Le Clanché type, the improved spacer may be used with numerous other cells in which similar results are sought.

40 I claim:

45 1. A galvanic cell comprising a container, a depolarizing bobbin therein, a spacer comprising a member with marginal portions lying substantially on the circumference of a circle having a diameter approaching the inner diameter of the container, whereby substantial lateral movement of the spacer

in the container is prevented, said member having further marginal portions defining a central area approximating that of the base 50 of the bobbin and adapted to retain the same in such central area.

2. A galvanic cell comprising a container, a depolarizing bobbin therein, a spacer comprising a sheet having corners adapted to 55 engage the side walls of the container, said sheet having tangs upturned between the corners and adapted to receive the bobbin snugly therebetween.

3. A dry cell comprising a zinc cup, a depolarizing bobbin therein, a spacer comprising a sheet having in general the outline of a polygon inscribed in a circle of a diameter approaching the inner diameter of the cup, said sheet having bobbin retaining portions 65 thereon defining a central area approximating that of the base of the bobbin and adapted to retain the same in such central area. 60

4. A dry cell comprising a zinc cup, a depolarizing bobbin therein, a spacer comprising a generally hexagonal sheet of insulating material shaped to fit snugly within the cup and having tangs thereon at points between the vertices of the hexagon defining a central seat for the bobbin. 70

5. A dry cell comprising a zinc cup, a depolarizing bobbin therein, a spacer comprising a sheet of insulating material shaped to fit snugly within the cup and having tangs thereon scored along their line of junction 80 with the sheet for bending upward to engage the base of the bobbin and to center it with respect to the cup. 75

6. A dry cell comprising a zinc cup, a depolarizing bobbin therein, a spacer comprising substantially rigid portions adapted to engage the side walls of the cup and to fit snugly therein and flexible portions adapted to bend upwardly about the bobbin and hold it in central position. 85

90 In testimony whereof, I affix my signature.

ARTHUR J. BRIGGS.
